(57) CLAIM

The ornamental design for a tile dispenser for a game, as shown and described.

DESCRIPTION

FIG. 1 is a perspective view of a first embodiment of a tile dispenser for a game of the claimed design;

FIG. 2 is a perspective view thereof, shown with a portion of the tile dispenser for a game moved into a different position;

FIG. 3 is a top plan view thereof;

FIG. 4 is a left side elevational view thereof;

FIG. 5 is a right side elevational view thereof;

FIG. 6 is a rear elevational view thereof; and,

FIG. 7 is a front elevational view thereof.

The bottom of the tile dispenser is unornamented and not part of the claimed design. The features shown in broken lines are environment only and not part of the claimed design.
